UNITED STATES PATENT OFFICE.

LEONARD DAY, OF NEW YORK, N. Y., ASSIGNOR TO FEDERAL SIGNAL COMPANY, A CORPORATION OF NEW YORK.

DETECTOR-BAR.

1,222,368.

Specification of Letters Patent.

Patented Apr. 10, 1917.

Application filed July 26, 1911. Serial No. 640,597.

To all whom it may concern:

Be it known that I, LEONARD DAY, a citizen of the United States, and a resident of the borough of Manhattan, city, county, and 5 State of New York, have invented certain new and useful Improvements in Detector-Bars, of which the following is a specification.

This invention relates to detector bars. 10 The invention seeks to provide a detector bar for railways that shall be convenient and reliable in its operation, economical to manufacture and which shall have the capacity of detecting the presence of a car 15 wheel by contact with the side face of the wheel.

One characteristic feature of the invention is that the bar has a longitudinal movement and, at the same time, is so arranged as to 20 have a tilting movement inward against the side face of a wheel. Another characteristic feature of the invention is that the bar is adapted to move into two detecting positions, one of said detecting positions being 25 against the tread of a wheel and the other detecting position being against the side face of a wheel, the bar presenting its detecting edge against the side face of the wheel by a tilting movement. Another characteristic 30 feature of the invention is that the bar is carried on supports, preferably pivotal, which supports rise to lift the bar, the bar being then tilted inward, in response to said lifting movement, against the side face of 35 a wheel.

In the accompanying drawings forming part of this specification, the invention is illustrated in two of the various forms in which the invention is capable of being embodied. In the drawings,

Figure 1 is a side elevation of a detector bar associated with the track rail.

Fig. 2 is an end view of the detector bar taken on the line 2—2 of Fig. 1.

Fig. 3 is a side elevation of another form of detector bar and embodying the invention.

Fig. 4 is an end view of the structure shown in Fig. 3, the rail being in section and 50 also the detector bar proper.

Referring now more particularly to the structure shown in the drawings, 1 is a clip secured to the rail 2 by the hook bolts 3 and 4 and the stud bolt 5. The clip is made

in channel form having guide plates 6 and 7 across which extends a bolt or stud 8 carrying the roller 9. 10 is the detector bar proper to which are secured the brackets 11 and 12. These brackets are pivotally mounted on stud bolts 13 and 14 which pass through the brackets and are fixed in the opposite ends of the motion plate 15 which supports the bar. Extending inward from the lower sides of the brackets and integral therewith are arms 16 and 17 which are 65 bifurcated at their inner ends to receive the rollers 18 and 19 which they carry. These arms 16 and 17 are in close proximity to the rail and beneath the head thereof.

The bar is arranged to have a longitudinal movement by suitable means such as those commonly now in use. In the normal position of the detector bar, its upper or detecting edge is in proximity to the rail head and beneath its upper surface, as shown in 75 Figs. 1 and 2. When the bar is given a longitudinal movement from right to left, the motion plate rides on the roller 9 and between the guide plates 6 and 7.

In this longitudinal movement the inclined 80 cam face 20 of the motion plate rides over the roller 9 and thereby causes the bar to rise so as to strike the tread of the car wheel on the rail, if the tread of the wheel is projecting beyond the rail head. This brings 85 the bar into its first detecting position. If the wheel on the rail 2 is not projecting beyond the head of the rail, the longitudinal movement of the bar continues, and as the cam face 20 continues riding on the roller 90 9, the bar rises still higher. But, at the same time, it is tilted inward by the arms 16 and 17 whose rollers have come against the under side of the rail head, thereby causing the bar to be tilted inward over the rail 95 head. Thus, the bar is brought into its second detecting position. If the wheel on the rail 2 does not project beyond the side of the rail head, the bar will strike the side face of the wheel before it reaches the limit 100 of its tilting movement. The continued longitudinal movement of the bar then causes the horizontal cam face 21 and the inclined cam face 22 to ride over the roller 9. This causes the bar to travel along for a short 105 distance in its extreme upper position and then to descend to its lower position. A reverse longitudinal movement of the bar

Referring now more particularly to the structure shown in the drawings, 1 is a clip secured to the rail 2 by the hook bolts 3 and 4 and the stud bolt 5. The clip is made

thereafter causes the bar to rise and fall in the same way, returning to its initial position.

In Figs. 3 and 4 the bar is supported on swinging parallel arms 23 and 24 mounted on the pivot bolts 25 and 26 secured to the clips 27 and 28. The bar is fixed to brackets, such as 29, each of which is pivotally mounted on the rod 30 whose ends are fixed in socket pieces 31 and 32 pivotally secured to the upper ends of the arms 23 and 24. The bracket 29 has rigidly connected with it an inwardly projecting arm 33 carrying a roller 34 similar to the arrangement shown in Figs. 1 and 2.

The movement of the bar shown in Figs. 3 and 4 is similar to that described with reference to Figs. 1 and 2, but in Figs. 3 and 4, the upward movement of the bar is produced by the parallel arms 23 and 24. The tilting movement is produced by the arm 23 abutting against the under side of the rail head similar to that produced by the arms 16 and 17 in Figs. 1 and 2.

It will, of course, be understood that the bar is provided with a plurality of motion plates or parallel arms, and their associated parts, the number varying with the length of the bar and the requirements of good practice.

What I claim and desire to secure by Letters Patent is:—

1. A longitudinally moving detector bar; a pivotal support for said bar adapted to move longitudinally therewith; and means for causing said bar to tilt inward on its pivotal support against the side face of a wheel.

2. A longitudinally moving detector bar adapted to move into two detecting positions, one position being against the tread of a wheel and another position being against the side face of a wheel and horizontal pivots on which the bar is mounted so as to have the capacity, during its movement, to tilt against the side face of a wheel.

3. A longitudinally moving detector bar adapted to move into two detecting positions, one position being against the tread of a wheel and another position being against the side face of a wheel; a pivotal support for said bar adapted to move longitudinally therewith; and means for causing said bar to tilt inward on its pivotal support against the side face of a wheel.

4. A longitudinally moving detector bar; means for exerting an upward thrust on said bar; and means for causing said bar to tilt inward against the side face of a wheel in response to said upward thrust, said means comprising one or more arms carried by said bar and arranged to engage the under side of the rail head.

5. A detector bar; pivotal supports therefor; lifting means for said pivotal supports;

and means for tilting the bar inward against the side face of a car wheel in response to said lifting means.

6. A detector bar; pivotal supports therefor; lifting means for said pivotal supports; and arms carried by said bar arranged to tilt the bar inward against the side face of a car wheel in response to said lifting means.

7. A detector bar; pivotal supports therefor; lifting means for said pivotal supports; and arms carried by said bar arranged to strike the under side of the rail head and thereby tilt the bar inward against the side face of a car wheel in response to said lifting means.

8. A detector bar; supports therefor; lifting means for said supports; and arms carried by said bar arranged to strike the under side of the rail head and thereby tilt the bar inward against the side face of a car wheel in response to said lifting means.

9. A longitudinally moving detector bar adapted to move into two detecting positions, one position being against the tread of a wheel and another position being against the side face of a wheel; parallel arms pivoted to and supporting said bar and arranged to impart an up and down movement to the bar during its longitudinal movement; and means for guiding the bar inward over the head of a rail during its movement.

10. A detector bar adapted to move into two detecting positions, one position being against the tread of a wheel and another position being against the side face of a wheel; means comprising swinging arms for moving said bar into one of its detecting positions; and means for guiding said bar into its other detecting position during its movement.

11. A longitudinally moving detector bar adapted to move into two detecting positions, one position being against the tread of a wheel and another position being against the side face of a wheel; means comprising swinging arms for moving said bar into one of its detecting positions; and means for guiding said bar into its other detecting position during its movement.

12. A detector bar adapted to move over the head of the rail into a detecting position against the side face of a car wheel, in combination with arms arranged to swing longitudinally of the rail to carry the bar above and below the horizontal level of the rail head, pivots extending parallel with the bar and connecting said bar and arms, and provisions for moving the bar inward on said pivots during its movement by said arms and against the side face of a wheel.

13. A longitudinally moving detector bar adapted to move over the head of the rail into a detecting position against the side face of a car wheel, in combination with

arms arranged to swing longitudinally of the rail to carry the bar above and below the horizontal level of the rail head, pivots extending parallel with the bar and connecting said bar and arms, and provisions for moving the bar inward on said pivots during its movement by said arms and against the side face of a wheel.

Copies of this patent may be obtained for five cents each, by addressing the "Commissioner of Patents, Washington, D. C."

In testimony whereof, I have signed my name to this specification, in the presence 13 of two subscribing witnesses.

LEONARD DAY.
